RESILIENT RAIL SPIKE

Frederick A. Preston, Lake Forest, Ill., assignor,
by mesne assignments, to Poor & Company,
Chicago, Ill., a corporation of Delaware

Application January 3, 1938, Serial No. 183,006

11 Claims. (Cl. 238—366)

This invention relates to improvements in elastic rail spikes of unitary construction adapted to be driven into railway cross-ties and exert resilient pressure on the base flanges of the rails.

A principal object of the invention is to provide an improved rail spike of the above general character which, when driven to its applied position in a cross-tie, will exert resilient pressure on the base portion of a rail and will also effect a firm, but manually releasable interlocking engagement with a tie plate so as to prevent the vertical forces on the spike, for example, the vertical wave movements of a rail, from partially withdrawing the spike from the cross-tie or otherwise disturbing the resilient clamping action of the spike on the rail.

Another object of the invention is to provide a resilient spike adapted to exert a predetermined resilient pressure on a base flange of a rail when the spike is driven to its applied position and which is so formed that the parts thereof will assume positions relative to each other and/or relative to the tie plate to indicate that the spike is fully applied and therefore sufficiently tensioned to produce the desired spring pressure on the rail.

Another object of the invention is to provide a rail spike having a vertically resilient portion for engagement with a rail base flange and one or more laterally resilient portions which are compressed during movement of the spike through an opening in the tie plate and which expands below the bottom surface of the tie plate into frictional engagement with the cross-tie and provide a shoulder portion underlying the bottom surface of the tie plate to prevent undesirable upward movement of the spike relative to the plate.

Many other objects and advantages of the spike constructions herein shown and described will be obvious to those skilled in the art, from a disclosure herein given. It will be understood, therefore, that the present invention consists in the novel construction, arrangement and combination of parts hereinafter shown and described, together with all variations and changes in structure coming within the scope of the several claims.

In the drawings:

Fig. 1 is a side view in elevation of one approved form of a resilient rail spike made in accordance with this invention; the base flange of the rail, the tie plate and underlying cross-tie being shown fragmentarily and in section in this figure.

Fig. 2 is another view in elevation of the struc-

ture illustrated in Fig. 1; said view being taken from the left of Fig. 1.

Fig. 3 is a view similar to Fig. 2 illustrating a modified construction.

Fig. 4 is another view similar to Fig. 2 illustrating a further modified embodiment in its partially applied position.

Fig. 5 illustrates the rail spike of Fig. 4 in its fully applied position.

Fig. 6 is a view similar to Fig. 1 but illustrating a modified locking device and a somewhat different arrangement of the elements for holding the rail base and tie plate in spring clamped relation; and

Figs. 7 and 8 are fragmentary views illustrating further modifications of the upper end portion of the rail spike shown in Fig. 6.

Referring first to Figs. 1 and 2 of the drawings, 10 designates one base flange of a rail seated on a tie plate 11, 12 the cross-tie on which the tie plate and rail are supported, and 13 indicates a resilient rail spike driven into a pre-bored spike hole 14 in the cross-tie. The spike 13 is made, preferably, from a flat metal strip and is suitably tempered to provide the desired resilience. The metal strip herein shown is rectangular in cross-section and has a width which is substantially greater than its thickness. However, the form and size of the metal strip may be varied to suit the form and size of the spike being manufactured. The metal strip is bent upon itself to provide a split body composed of flexible members 15—15. The bend is preferably relatively sharp and the ends of the metal stock are pressed firmly together so that the wide flat faces of the metal are in substantial contact with each other for a portion of the length of the spike. The end of the spike body adjacent the fold or bend 16 is bent at an angle to the body portion

40 to provide a hook 17 adapted to overlie and bear resiliently against the marginal upper surface of the rail base 10. The said hook is preferably formed by bending the metal in the direction of its width so that the members 15—15 will stand edgewise to the top of the rail base and therefore provide great resilient strength for holding the rail clamped to the tie plate 11. The bend of the hook is also made relatively large so that the flexing thereof, during the application of the spike, to its applied position and during the vertical wave movements of the rail, will be distributed uniformly throughout the length of the hook. The bowed members 15—15 of the spike body are bowed outwardly, as indicated at 18, to provide laterally resilient portions

which expand and embed themselves into the wall of the pre-bored spike holes 14 in the cross-tie so as to provide a firm frictional engagement with the tie, the edge portions of the members 15-15 cutting into the circular walls of the bored hole 14. This expansion pressure against the walls of the opening in the tie plate holds the plate firmly on the top surface of the tie. The said outwardly bowed portions 18-18 also provide inclined shoulders 19-19 which interlock with the lower edges of the spike opening 20 in the tie plate 11 when the spike is driven to its applied position.

The position of the said shoulders 18-18 relative to the end of the hook 17 is such that the hook will engage the base flange 10 of the rail before the said shoulders on the spike body extend below the bottom face of the tie plate. Consequently the driving of the spike into the cross-tie a distance sufficient to engage the shoulders 19-19 beneath the lower edge of the spike opening 20 of the tie plate will impart a desired predetermined tension to the hook 17 of the spike. The tension of the hook holds the rail and tie plate in resilient clamped engagement. The shoulders 19-19 of the spike interlock with the tie plate so as to prevent the tension in the spike hook 17 from partially withdrawing the spike from the tie. The said interlock of the tie plate and spike makes it practicable to provide sufficient tension in the hook portion of the spike to hold the rail from creeping lengthwise across the tie. This creep-resisting function of the spike is made practicable by reason of the fact that the pressure exerted by all of the spikes along the rail will be substantially uniform and thereby cooperate as a group to resist the creeping pressure on the rail.

The resilient spike above described may be withdrawn from the cross-tie by the use of any suitable implement adapted to exert a vertical pull on the shank portion of the spike. During this operation the inclined shoulders 19-19 function as cam surfaces which engage the lower edges of the spike opening in the tie plate so as to compress the bowed portions 18 sufficiently to permit the spike to be moved upwardly through the spike opening 20 of the tie plate.

In the embodiment shown in Fig. 3 of the drawings, the members 15a-15a of the spike body are bowed outwardly to provide a more gradual taper than is shown for the corresponding element of Fig. 2 and the shoulders 21-21 for interlocking engagement with the tie plate are more abrupt than the shoulders 19 of Fig. 2. Preferably, the shoulders 21-21 are formed by offsetting members 15a-15a.

The shoulders 21-21 may be released from the interlocked position beneath the tie plate by compressing the resilient leg portions of the spike together. In order to facilitate this operation the resilient legs are provided at a suitable location above the tie plate with outwardly bowed portions 23 adapted to overlie the claw portions of the usual claw bar (not shown) which is ordinarily used to withdraw rail spikes from cross-ties. The said pronged portions of the claw bar, in pressing against the curved surfaces 24 of the said bowed portions of the spike, flex the members 15a-15a toward each other until the wide shoulder portions 21-21 will pass upwardly through the spike opening 20a in the tie plate. In other respects the spike shown in Fig. 3 of the drawings may be, and preferably is, the same as illustrated in Figs. 1 and 2. The common feature

of both constructions are, therefore, designated by the same reference numerals.

In the embodiment shown in Figs. 4 and 5, the bent or folded portion of the metal strip constitutes the lower end 25 of the spike and the laterally resilient leg portions 26 of the spike are spaced apart to provide a shank portion of general wedge shape, adapted to be driven into the pre-bored spike holes of the tie. At a suitable location 10 the laterally resilient portions 26 are bowed inwardly at 27-27 to provide shoulder portions 28-28 adapted to spring beneath the lower edge of the tie plate opening and interlocked therewith when the spike is driven to its fully applied position. The inwardly bowed portions 27-27 also provide upper shoulders 29-29 which prevent over-driving of the spike. The upper extremities of the leg portions 26-26 are bent into hook form substantially as shown in Fig. 1. These hooks, for the purpose of convenience, are designated by the reference numerals 17b-17b.

When driving the spike illustrated in Figs. 4 and 5 to its applied position, the upwardly diverging members 26-26 of the spike press against opposite side walls of the spike opening 20b of the tie plate and are thereby flexed toward each other, substantially as shown in Fig. 4. When the shoulders 28-28 clear the lower edges of the spike opening in the tie plate, the members 26-26 will expand outwardly into the wooden cross-tie and the shoulders 28-28 will assume their locking positions beneath the bottom face of the tie plate. At this time the shoulders 29-29 of the spike are in close relation to the top surface of the tie-plate and therefore give visual indication that the spike has reached the position necessary to effect the desired tension in the hook ends 17b-17b. The upper shoulders 29-29, in addition to giving a visual indication of the proper applied position of the spike, serve as means for positively holding the tie plate clamped to the top surface of the cross tie.

When it is desired to remove the spike (Figs. 4 and 5) from its applied position, the resilient leg portions 26-26 are pressed together until the lower shoulders 28-28 will pass upwardly through the spike opening of the tie plate.

The modified embodiment shown in Figs. 6, 7 and 8 comprise, in each case, a metal strip bent upon itself so as to provide upwardly diverging legs 30-30 which expand into the wood cross-tie in the same manner as previously described. One leg 30 is preferably bent flatwise into hook form so as to provide a resilient hook 31 which bears with its relatively wide flat surface on the top surface of the rail base 10. The other diverging leg 30 is provided with means for locking engagement with the tie plate, and the upper end of the last mentioned leg is bent upwardly, as indicated at 32. The outwardly bent portion 32 provides a curved under surface which functions as a cam surface when engaged by the claw portions of a claw bar to force the spring legs 30-30 toward each other and, therefore, permit the spike to be withdrawn from its applied position. The spring pressure of the outwardly diverging member 30-30 against the walls of the spike openings in the tie plate 33 functions to hold the tie plate relatively fixed on the top surface of the cross-tie 34. In this respect the modifications in Figs. 6, 7 and 8 function in the same manner as the laterally resilient portions of all previous embodiments described herein. However, the means for interlocking the spikes with the bottom surface of the cross-tie

is somewhat different in the three figures. The locking shoulder 35 shown in Fig. 6 is preferably formed by offsetting the outer member 30 of the spike shank. The locking shoulder 36 of the embodiment shown in Fig. 7 is formed by bowing the outer spring arm of the key inwardly, as indicated at 37. This construction like the similar construction shown in Figs. 4 and 5 provides also an upper shoulder 38 which assumes a position in close relation to the top surface of the tie plate 39 when the spike member is driven to its fully applied position. The said shoulder 38 functions not only as an indicator to show when the spike has been driven into the tie sufficient to impart the desired tension to the resilient hook portion, 15 but also provides a positive means for holding the tie plate clamped to the top surface of the tie. The locking shoulder 40 of the embodiment shown in Fig. 8 is formed by bowing the outer spring arm of the spike outwardly, as indicated at 41. The clearance 42 between the resilient arm portions of the spike when it is in its applied position is normally sufficient to permit the bowed portion 41 to pass upwardly through the spike 25 opening of the tie plate when the resilient arms are pressed together. In other structural and functional respects the spike structures illustrated in Figs. 6, 7 and 8 may be the same. The several parts of the spike shown in Figs. 7 and 8 which correspond to the structure of Fig. 6 are therefore given the same reference numeral with the exponents *a* and *b*, respectively.

I claim:

1. A rail spike comprising a portion for overlying the base flange of a rail and having a shank portion adapted to be driven through an opening in a tie plate and into an underlying cross-tie, and means formed integral with the shank adapted to flex laterally beneath the plate into locking engagement therewith when the spike is driven to its applied position in the cross-tie, there being a portion of said means projecting above the tie plate and spaced from an adjacent portion of the shank, whereby reverse flexing thereof releases said locking engagement.

2. A rail spike comprising a portion for overlying the base flange of a rail and having a shank portion adapted to be driven through an opening in a tie plate and into an underlying cross-tie, and means comprising a relatively abrupt shoulder integral with the shank adapted to flex laterally beneath the plate into locking engagement therewith and into spring gripping engagement with the cross-tie when the spike is driven to its applied position in the tie, there being a portion of said means projecting above the tie plate and spaced from an adjacent portion of the shank, whereby reverse flexing thereof releases said locking and spring gripping engagements.

3. A rail spike comprising a metal strip bent upon itself to provide a shank having spaced apart and laterally resilient legs adapted to be driven through an opening in a tie plate and into an underlying cross-tie, one of said legs being offset adjacent the bottom of the tie plate to provide a shoulder for interlocking engagement with the plate, a hook portion at the upper end of the shank for resilient engagement with the upper surface of a rail base positioned on said plate, and means positioned above the tie plate for engagement with a spike pulling implement, the said means being provided with an inclined surface which functions as a cam to press the legs of the shank together and thereby release the

said shoulder from interlocking engagement with the tie plate.

4. A rail spike comprising a metal strip bent upon itself to provide a shank having laterally resilient legs spaced apart both above and below a railway tie plate and adapted to be driven through an opening in the tie plate and into an underlying cross-tie, one of said legs being bowed inwardly adjacent the tie plate to provide shoulders embracing the upper and lower edges of the tie plate opening, and means at the upper end of the shank for resilient engagement with the top surface of a rail base positioned on the plate.

5. A rail spike comprising a metal strip bent upon itself to provide a shank having upwardly diverging legs adapted to be driven through an opening in a tie plate and into an underlying cross-tie, one leg being bent at its upper end into hook form to engage the top surface of a rail base positioned on the plate and the other leg of the shank being formed with a shoulder for engagement with the lower edge of the tie plate opening and having an out-turned upper end for engagement with a spike pulling element.

6. A rail spike comprising a metal strip bent upon itself to provide a shank having upwardly diverging legs adapted to be driven through an opening in a tie plate and into an underlying cross-tie, one leg being bent at its upper end into hook form to engage the top surface of a rail base positioned on the plate and the other leg of the shank being bowed to provide a shoulder for locking engagement with the lower edge portion of the opening in the tie plate and having an out-turned end for engagement with a spike pulling implement.

7. A rail spike comprising a metal strip bent upon itself to provide a shank having upwardly diverging legs adapted to be driven through an opening in a tie plate and into an underlying cross-tie, one leg being bent at its upper end into hook form to engage the top surface of a rail base positioned on the plate and the other leg of the shank being bowed inwardly to provide shoulder portions for locking engagement with the upper and lower edge portions of the opening in the tie plate and having an out-turned end for engagement with a spike pulling implement.

8. A rail spike formed at one end with a portion adapted to engage a rail base of a railroad rail to clamp the rail to its supporting structure and having a shank portion adapted to be driven into said supporting structure; the said shank being provided with an integral resilient portion for exerting lateral holding pressure against said supporting structure, and the said resilient portion being spaced from an adjacent portion of the shank both above and below the top surface of said supporting structure, whereby said holding pressure may be released by flexing the upper end of said resilient portion inwardly toward the other portion of the shank.

9. A rail spike comprising a metal strip bent upon itself to provide a laterally expandable shank portion adapted to be driven into a supporting structure underlying a railroad rail and having a vertically resilient portion for clamping the rail to said supporting structure; and means comprising a shoulder on one of said shank portions for resiliently engaging a portion of said supporting structure, and the said expandable portion being spaced from the other portion of the shank both above and below the top surface of said supporting structure, whereby said shoulder may be released from its engagement with the supporting

structure by flexing the upper end of the shank portion, on which said shoulder is formed, toward the other portion of the shank.

10. A rail spike comprising a metal strip bent upon itself to provide a shank having expansible leg portions adapted to be driven into a supporting structure underlying a railroad rail, and a hook at one end of the shank for resiliently clamping the rail to said supporting structure; one of the legs of said shank portion being displaced outwardly to provide a relatively abrupt shoulder adapted to flex into releasable interlocking engagement with said supporting structure, and the said expansible legs being spaced from each other both above and below the top surface of said supporting structure, whereby said shoulder may be released from its engagement with the supporting structure by flexing the

upper end of the leg, on which the shoulder is formed, toward the other leg portion of the shank.

5 11. A rail spike comprising a portion for overlying the base flange of a rail and having a shank portion adapted to be driven through an opening in a tie plate and into an underlying cross-tie; the said shank being formed with an integral resilient portion adapted to flex laterally into releasable interlocking engagement with the lower edge of said spike opening when the spike is driven to its applied position; there being a portion of the shank above the tie plate spaced from an adjacent portion of the shank 10 and adapted to be compressed toward the said other portion of the shank to release said interlocking engagement.

FREDERICK A. PRESTON.
